UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

SUPPORT.

1,205,234.

Specification of Letters Patent. Patented Nov. 21, 1916.

Application filed November 10, 1913. Serial No. 800,138.

To all whom it may concern:

Be it known that I, RONALD F. McFEELY, a citizen of the United States, residing at Beverly, in the county of Essex and State 5 of Massachusetts, have invented certain Improvements in Supports, of which the following description, in connection with the accompanying drawings, is a specification, like reference characters on the drawings indicating like parts in the several figures.

The object of this invention broadly is to provide a device in the nature of a support which may form a convenient attachment for structures of various kinds in connection with which its use may be desirable, and particularly to provide such an attachment for an upright member such as the supporting column or standard of a machine frame, and one that may be readily secured in position or detached when desired and may have provision for movement with reference to its supporting member so as to be out of the way when not in use.

25 In the manufacture of boots and shoes a machine known as the pulling over machine, illustrated in United States Letters Patent No. 1,029,387, granted June 11, 1912, is employed for pulling the upper over the last and securing its edges temporarily in position upon the insole prior to the lasting operation. The operative parts of this machine are mounted upon a tall supporting column so that the shoe is located in the

35 machine at about the height of the operator's head. For holding the tacks and feeding them automatically to the driving devices, there is provided a receptacle known as the tack pot together with tack separating and feeding devices which are located near the upper extremity of the machine. It becomes necessary frequently for the operator to inspect the feeding mechanism, but neither this inspection nor 40 that of other mechanisms at the top of the machine could be readily effected heretofore unless there happened to be available a ladder or other support upon which the operator could climb.

50 A particular object of this invention is to provide, as an attachment for the frame of such a machine, a support which will be ready for use at all times for the purpose above set forth, and yet so arranged that

when not in use it may form no obstruction 55 to the free movements of the operator about the machine. It should be understood, however, that although the use of the device is contemplated as particularly advantageous in connection with this machine, the 60 invention is not limited to this particular use but is broadly applicable to various other uses wherever found convenient or desirable.

To the ends above set forth the invention 65 comprises, in its preferred embodiment, a novel arrangement of supporting means including a bracket which may be readily attached to or removed from a machine standard, and a step or rest mounted on the 70 bracket and preferably movable with reference thereto so as to be out of the way when not in use but adjustable instantly to operative position when desired.

These and other features of the invention 75 including certain details of construction and combinations of parts will now be described with reference to the accompanying drawings and pointed out in the claims.

In the drawings, Figure 1 is a perspective 80 view showing a preferred form of the device in operative position upon a supporting standard such as that used in the pulling-over machine, Fig. 2 is a fragmentary view illustrating the manner of attaching the device to the machine standard, and Fig. 3 is a side view showing in dotted lines the inoperative position of the step.

The supporting base or standard of a pulling-over machine is indicated generally 90 by the numeral 2. The commercial machine is provided with an opening 4 in order to facilitate the assembling of the different parts, and the bracket 6 of the supporting device of this invention is shown as attached 95 to the machine by means of a bolt 8 extending through this opening, although it will be understood that the device may be attached to the machine at any other point desired by means of an opening formed 100 especially for the purpose. Since the opening 4 is of greater diameter than the bolt, a collar 10 is provided as a backing member for the bolt head. The bracket 6 is formed with three projections 12 which provide a 105 three-point bearing upon the frame of the machine so that any irregularity in the frame castings may be compensated for and

the bracket fitted accurately in the position desired. Since the securing means preferably consists simply of the single bolt 8, which engages the bracket within the area 5 between its three bearing points, the bracket is provided with lugs 14 which are arranged to embrace the sides of the frame or standard and thereby prevent the bracket from turning upon the bolt. The bracket is provided also with grooves or curved portions 10 16 at points opposite the fillet 18 with which the frame of the machine is usually provided, this means also serving to assist in maintaining the bracket in position.

15 Mounted upon the bracket is the step or rest 20 by the use of which the operator is enabled to view the interior of the tack pot and other portions of the machine head. The bracket is provided with a pair of hook 20 shaped bearings 22 in which are mounted a pair of trunnions 24 carried by the step. The step is provided with a pair of heel pieces 26 which are shaped to engage the bracket so as to sustain the step in a sub- 25 stantially horizontal position for use. By this arrangement it will be seen that the position of the step with reference to the bracket may be predetermined with reasonable accuracy. The step is readily detachable from the bracket when the latter is removed from the machine by reason of the hook shaped construction of the bearings 22, but the bearings and other portions of the bracket are so formed with reference to 30 the support to which the device is to be attached that when the bracket is in position the trunnions 24 cannot be removed from the bearings. The step will thus be always ready for use without the liability of becoming lost or misplaced. At the same time 35 the construction provides that the trunnions 24 shall be so spaced from the machine frame as to permit the step to be turned up and inclined against the frame when its use 40 is not required, as indicated by dotted lines in Fig. 3, so as to afford no obstruction to the movements of the operator about the machine.

It will be noted that the bracket 6 and the 50 step 20 with the single attaching bolt constitute the entire device, and both the bracket and the step can be cast complete, requiring no machine work. In these respects this attachment has been designed so that it can be manufactured at a small cost, and it can 55 be easily attached by its single bolt to machines which are already in use.

Although I have shown and described a 60 device having the particular features of construction above set forth, it should be understood that suitable variations may be made therein for the purpose of adapting the device to frames or standards of different construction or with a view to other 65 uses to which the device may be applied,

and that such variations are within the spirit and scope of the invention, as defined in the claims.

Having described the invention, what I claim as new and desire to secure by Letters Patent of the United States is the following:

1. A device of the class described comprising, in combination, a bracket adapted to be attached to a supporting member and having 75 bearings formed thereon, and a rest provided with trunnions pivotally mounted in said bearings and having also means for engaging the bracket to hold the rest projected in a substantially horizontal position for use, 80 said bearings being suitably positioned with reference to the supporting member to permit the rest to be turned up and inclined toward said member when not in use and comprising hooks the free ends of which 85 project in such relation to the supporting member as to prevent removal of the trunnions from said bearings while the bracket is attached to said member.

2. A device of the class described comprising, in combination, a bracket adapted to be attached to a supporting member and provided with open hook-shaped bearings having their open ends facing toward said supporting member, a rest having trunnions 90 projecting therefrom in position to enter the open sides of said bearings and pivot the rest for swinging movement relatively to the bracket, and means for maintaining the rest in a substantially horizontal position for use, 95 said bearings being supported with their open ends closed against the supporting member so as to prevent removal of the trunnions when the bracket is in operative position.

3. A device of the class described comprising, in combination, a bracket adapted to be attached to an upright standard and provided with a pair of hook-shaped bearings open at their rear sides, a rest having trunnions for engaging in said bearings, the bearings being constructed to prevent removal of the trunnions when the bracket is in position on the standard, means for engaging the bracket below said bearings to secure it to the standard, and lugs projecting from the bracket adjacent to the bearings in position to embrace the standard at opposite sides to determine the angular relation of the bracket to the standard. 110

4. In a device of the class described, the combination with a rest, of a bracket for supporting said rest adapted for attachment to an upright standard, a bolt for securing the bracket to said standard, and lugs on the bracket constructed to project at opposite sides of the standard to prevent the bracket from turning with reference to its point of attachment. 125

5. In a device of the class described, the 130

combination with a rest, of a support upon which said rest is mounted comprising a bracket adapted for attachment to an upright standard and constructed to have a three point bearing upon said standard, a bolt engaging the bracket within the area between said bearing points to secure the bracket to the standard, and a pair of lugs projecting from the bracket at opposite

sides of the standard to determine the angular relation of the bracket to the standard. 10

In testimony whereof I have signed my name to this specification in the presence of two subscribing witnesses.

RONALD F. McFEELY.
